United States Patent Office

Des. 228,709
Patented Oct. 23, 1973

228,709

CANOPY BEDSTEAD

Jack Klotz and Louise Klotz, Los Angeles, Calif., assignors to Environmental Concepts Products Co., Inc., Beverly Hills, Calif.

Filed Nov. 24, 1971, Ser. No. 202,058

Term of patent 14 years

Int. Cl. D6—01

U.S. Cl. D6—83

FIG. 1

FIG. 2

FIG. 3

FIG. 4

FIG. 1 is a perspective view of a canopy bedstead showing our new design;

FIG. 2 is an end elevational view;

FIG. 3 is a top plan view, the bottom plan being substantially a mirror image thereof; and

FIG. 4 is a side elevational view.

We claim:

The ornamental design for a canopy bedstead, as shown and described.
